(57) CLAIM

The ornamental design for a table with umbrella holder as shown and described.

DESCRIPTION

FIG. 1 is a front view of a table with umbrella holder showing my new design;
 FIG. 2 is a rear view of the table with umbrella holder;
 FIG. 3 is a right side view of the table with umbrella holder;
 FIG. 4 is a left side view of the table with umbrella holder;
 FIG. 5 is a top view of the table with umbrella holder;
 FIG. 6 is a bottom view of the table with umbrella holder; and,

FIG. 7 is a top front side perspective view of the table with umbrella holder.

The broken lines in FIG. 6 are illustrative of portions of the table with umbrella holder forming no part of the claimed design.

1 Claim, 5 Drawing Sheets
